G. B. OWENS,
DIRECTION INDICATING SIGNAL,
APPLICATION FILED JUNE 1, 1920.

1,392,442.

Patented Oct. 4, 1921.

Fig. 1.

UNITED STATES PATENT OFFICE.

GEORGE B. OWENS, OF MERRIAM, KANSAS.

DIRECTION-INDICATING SIGNAL.

1,392,442.

Specification of Letters Patent.

Patented Oct. 4, 1921.

Application filed June 1, 1920. Serial No. 385,515.

To all whom it may concern:

Be it known that I, GEORGE B. OWENS, a citizen of the United States, residing at Merriam, in the county of Johnson and State 5 of Kansas, have invented certain new and useful Improvements in Direction-Indicating Signals, of which the following is a specification.

This invention relates to direction indicating signals for motor and other vehicles, 10 and one object is to provide reliable devices which can be readily mounted upon the rear fenders or other suitable parts of the vehicle to indicate to approaching vehicles and 15 pedestrians the direction in which the vehicle equipped with the signals is to turn.

A further object is to provide novel electro-mechanical means for actuating signal blades, said means including electromagnets 20 and a circuit controlled by a suitable switch or push button mounted within convenient 25 reach of the driver.

Another object is to improve and simplify 30 the construction of direction indicating signals, in order to render them more practical, reliable and efficient in operation.

Other objects will hereinafter appear, and 35 in order that the invention may be fully understood, reference will now be had to the accompanying drawing, in which:

Figure 1 is a perspective view of one of 40 the devices mounted upon the fragmentary portion of a rear fender.

Fig. 2 is an irregular vertical section on 45 line II-II of Fig. 3.

Fig. 3 is a vertical cross section on line 50 III-III of Fig. 2.

Fig. 4 is a diagrammatic view.

In practice when the invention is applied 55 to an automobile, a signal device is, preferably, mounted on each fender A. Each device includes a case 2 inclosing most of the electrical apparatus and secured to the respective fender A by suitable means such as bolts 4.

6 designates a hollow frame fixed to the case 2 and carrying two rockably-mounted signal blades 8 and 10. The upper blade 8 extends over the top of the case 2 and is 60 provided at its ends with trunnions 12, journaled in the vertical sides of the frame 6. The lower blade 10 is provided at its ends with trunnions 14, one of which is journaled in one end of the frame 6 and the other in 65 the adjacent side of the case 2.

The blades 8 and 10 are provided with

fixedly-mounted arms 16 and 18, respectively, pivoted at their ends to a connecting rod 20 which extends through a slot 22 in the upper blade 8. The connecting rod 20 is 60 controlled by a lever 24 extending into the upper portion of the case 2 and mounted upon a fulcrum 26. The lever 24 is equipped with an armature 28, disposed above an electromagnet 30 secured to the bottom of the 65 case 2.

32 designates a rod pivotally connected at its upper end to the lever 24 and at its lower end to the spring contact 34 of a circuit breaker 36 arranged in the lower portion of 70 the case 2. The spring contact 34 normally holds the blades 8 and 10 in the horizontal or inactive position disclosed on Fig. 1, through the intermediary of the rod 32, the lever 24, the connecting rod 20 and the 75 arms 16 and 18.

40 designates a lamp, preferably, of the incandescent type arranged within the case 2, which in addition to an opening 42 through which the lever 24 extends, has an 80 opening 44 in its upper wall and openings 46 in its front and rear walls through which light from the lamp may illuminate the blades 8 and 10. A glass plate 48 is placed in the opening 44 to exclude dust from the 85 case 2 and the openings 46 which are normally closed by doors 50 having glass plates 52. By opening either of the doors 50 access may be had to the mechanism within 90 the case 2.

The electromagnets 30 are in a circuit 95 consisting of a wire 54, a wire 55, a wire 56, a blade 57, and a wire 58. The wires 54 and 58 are connected at one end to switch points 60 and 62, respectively, disposed at opposite sides of a switch 64 which in practice is, preferably, located on the dash within convenient reach of the driver. The lamps 40 are in branch circuits consisting of wires 66 and 68, a wire 70, a wire 72 and a switch 74. The circuits receive current 100 from a suitable source, such as a battery 75.

Normally the signal blades 8 and 10 are held in horizontal or inactive position, so 105 that they cannot be readily seen by approaching pedestrians or the drivers of other vehicles. When the driver is about to turn to the left he so indicates his intention by throwing the switch 64 into engagement with the switch point 60 to close the circuit 110 through the wires 54, 55 and 56 and energizes the electromagnet 30 at the left. As

said electromagnet is energized it attracts the associated armature 28 against the action of the spring contact 34 and causes the lever 24, through the intermediary of the intervening parts, to rock the blades 8 and 10 at the left to active position, so that they can be readily seen. After the turn has been made, the switch 64 is opened to interrupt the circuit through the magnet 30, so that the blades 8 and 10 may be restored to inactive position through the intermediary of the spring contact 34 and the intervening mechanism. At night the driver also closes the switch 74, so that the lamp 40 at the left 15 will be lighted on closing of the circuit breaker 36 through the downward movement of the lever 24 when its armature 28 is attracted by the electromagnet 30. As the lamp is lighted the rays illuminate the blades 8 and 10, so that they can be plainly seen by 20 pedestrians approaching from the front or rear. If the driver is to turn to the right, he so indicates by throwing the switch 64 into engagement with the switch point 62 to dis- 25 play the blades 8 and 10 mounted on the rear fender of the automobile.

The blades 8 and 10 are, preferably, enameled white so that they may be plainly seen when in active position. Instead of 30 providing independent circuits for the electromagnets 30 and the lamps 40, the same may be connected up in any suitable manner with the regular system with which modern cars are equipped.

35 While I have shown and described the device as being electrically controlled it is obvious that the blades 8 and 10 can be mechanically actuated by attaching a cable to the rod 32 and running said cable over 40 guides to the dash.

From the foregoing description it is apparent that I have produced signaling means embodying the advantages above pointed out, and while I have shown and described the preferred construction, combination and arrangement of parts, I reserve the right to make such changes as properly fall within the spirit and scope of the claim. 45

Having thus described my invention what I claim and desire to secure by Letters Patent, is:

A device of the character described, consisting of a rockably-mounted signal blade, a lever associated with said blade to rock the same to active and inactive positions, an armature on said lever, a normally deenergized electromagnet, a main circuit to energize said electromagnet and cause the same to attract the armature and effect rotation of the blade to active position through the intermediary of the lever, a branch circuit connected to the main circuit, a lamp in said branch circuit to illuminate the signal blade when said branch circuit is closed, a circuit breaker connected to the branch circuit and including a spring contact, and a rod operably connecting said spring contact and the lever so that the latter may close the circuit breaker when the armature is attracted by the electromagnet and whereby 70 said spring contact may open the branch circuit and restore the blade to inactive position through the intermediary of the lever when the electromagnet is deenergized. 65

In testimony whereof I affix my signature 75 in the presence of two witnesses.

GEORGE B. OWENS.
